UNITED STATES PATENT OFFICE.

FRIEDRICH W. KÖTTGEN, OF BARMEN, PRUSSIA.

IMPROVEMENT IN PUMPING-ENGINES.

Specification forming part of Letters Patent No. **178,163**, dated May 30, 1876; application filed April 22, 1876.

To all whom it may concern:

Be it known that I, F. W. KÖTTGEN, of Barmen, Kingdom of Prussia, have invented an Improved Pumping-Engine, of which the following is a specification:

This invention relates to an arrangement of pumping-engines by which certain important advantages are attained over the constructions at present in use.

The engine is arranged with two cylinders, A A', properly supported on beams and columns. Below the cylinders is placed a crank-shaft, B, with a fly-wheel, D, the connection between the piston-rods and the cranks, as well as the arrangement of the guides, being similar to that of the engines called "inverted-cylinder engines." The two cranks, however, are not placed at an angle of ninety degrees to each other, as usual, but in opposite directions—*i. e.*, at an angle of one hundred and eighty degrees, so as thereby to balance the two sets of pump-rods and other parts in reciprocating motion. The piston-rods E E' pass through the tops of the cylinders, and the upper end of each of them is attached to the end of an oscillating beam in the usual style of beam-engines. The two beams F F', however, converge toward each other, so that their extreme ends, to which the pump-rods G G' are attached, are brought close together over the shaft of the mine, or, in general, over the two sets of pumps.

The arrangement of the steam-valves, the valve-gearing, condensers, &c., may be made in any desired manner, and, instead of two single cylinders, any convenient combination of high and low pressure cylinders may be adopted; also, the arrangement of the engines may be inverted, so as to have the crank-shaft above and the beams below.

The cylinders are placed at such a distance from each other as to secure a proper length of shaft between its two bearings, and a fly-wheel is fixed on the center of the shaft.

The two cranks being placed opposite to each other, as stated, it is necessary to cast the fly-wheel with teeth on its rim, and to arrange a lever with a pawl, (which may be moved by a small steam-engine,) for the purpose of turning the cranks over the dead-center before starting the engine, in case it should have stopped at this point.

The angular position of the two wrought-iron beams will be seen from the elevation, Figure 1, as well as from the ground plan, Fig. 2, while Fig. 3 shows the crank-shaft, &c., in plan.

The weight of the pump-rods and appendages I prefer to calculate so that it materially overbalances the head of water acting on the plungers, so as to have a constant tensile strain on the moving parts of the engine, the keys thereby being prevented from working loose.

The advantages which my arrangement presents consist in the following: First, an efficient expansion of steam of any desired grade is thereby to be attained, while in the common pumping-engines without fly-wheel the expansion is, in practice, not to be carried out to any effectual amount, although the design of the valve-gear may be adapted for the purpose. Second, as by the arrangement of the engine and of a double set of pumps the weights of all the parts in motion, as well as the momenta of the same, are completely balanced, the engine may run at a much higher speed, and it may make a greater number of strokes, in comparison to former constructions, without rotative motion, as well as to the more recent pumping-engines with fly-wheels. Third, the engine presents all the advantages of the underground pumping-engines, while the disadvantages of the latter, especially their liability to be swamped by an accidental rise of water in the mine, are removed.

I claim as my invention—

1. In a pumping-engine, the combination of the beams F F', operating the pumps, with the piston-rods E E', cylinders A A', crank-shaft B, and intermediate fly-wheel D, all arranged substantially in the manner described.

2. In a pumping-engine, the combination of the piston-rods and pump-rods with the beams F F', arranged at an angle in respect to each other, as set forth.

In testimony whereof I have signed my name to this specification in the presence of two subscribing witnesses.

FRIEDRICH WILHELM KÖTTGEN.
